UNITED STATES PATENT OFFICE.

GEORGE HENRY TRIFTSCHAUSER, OF ATTICA, NEW YORK.

AUTOMATIC CLUTCH RELEASE FOR TRACTORS.

Application filed October 21, 1922. Serial No. 596,038.

To all whom it may concern:

Be it known that I, GEORGE H. TRIFTSCHAUSER, a citizen of the United States, residing at Attica, in the county of Wyoming and State of New York, have invented a new and useful Automatic Clutch Release for Tractors, of which the following is a specification.

This invention relates to tractors and more particularly to attachments for releasing the clutch on the rearing of the tractor.

The object of the invention is to provide a simple and efficient device of this character whereby when the front axle and wheels of the tractor rise incident to the rearing of the tractor, the clutch will be automatically disconnected and remain so until the front wheels of the tractor descend into normal position.

Another object is to provide a device of this character which does not in any way obstruct clearance, is positive in action, and very simple and durable and can be manufactured and sold cheaply.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a side elevation of a portion of a Fordson tractor engine with this improved attachment shown applied, parts being in section.

Fig. 2 is a side elevation of one of the castings used in connection with this attachment.

Fig. 3 is a front elevation of said casting.

Fig. 4 is an elevation taken from the inside of one member of one of the front castings; and

Fig. 5 is a side elevation thereof.

In the embodiment illustrated, a tractor engine is shown at E and the clutch control lever or pedal at CP.

The attachment constituting this invention comprises a casting 1 for connection with the crank case of the engine and a casting 10 designed to be mounted on the front axle A of the tractor. A cable 20 connects the axle casting 10 with the clutch

pedal CP, said cable being united with the pedal by a clip 21 and passing over and around suitably located pulleys 22, 23, 24, 25 and 26 which guide the cable and prevent its binding when a pull is exerted thereon. The front end of this cable is connected with an eye bolt 27 secured to the trunnion pin 28 which passes through the casting 10 in a manner presently to be described.

The casting 1, designed to support the radius rod R, takes the place of the mounting usually employed for this rod. This casting 1 has an upstanding shank 2 which is designed to be located between spaced lugs L and L', which depend from the crank case c. This shank 2 is apertured for the passage of the connecting bolt 3. The lower portion of the casting is bifurcated and the furcations 4 and 5 have registering apertures for the passage of the radius rod R, said apertures forming in conjunction a tapered bore 6, the larger end extending toward the front portion of the engine to provide for the rocking of the radius rod when the front axle drops incident to the rearing of the tractor, as will be hereinafter more fully described.

A brace arm 9 cast integral with the casting 1 is secured to the engine crank case to reinforce the casting and hold it rigidly in operative position.

The front axle A is ordinarily connected with the crank case of the engine by a bifurcated casting, the arms a and a' of which straddle the axle and are secured thereto by a trunnion pin which passes through apertures in said arms and in the axle. The casting 10 which constitutes a part of this invention and which is designed to carry the trunnion pin 28, encases the arms a and a' of the usual axle casting.

This casting 10 is composed of two members 11 and 15 which are constructed exactly alike and designed to straddle the axle A and the casting carried by the engine tractor. Each of these members is provided on its inner face with laterally extending arms 12 and 13 which, when the members are assembled, are designed to abut and which have bores 14 passing therethrough to receive clamping bolts for securing the members in operative position. Between the arms 12 and 13 of each casting is a chamber or recess 16 designed to receive the castings on the tractor which normally engage the

axle and projecting laterally from the side walls of this chamber are nipples as 17 which fit in the apertures in the casting arms a and a' where the trunnion pin is normally applied and which retain the casting 10 from sliding downward when the tractor rises. The lower ends of the members 11 and 15 are provided with longitudinally extending slots as 18, through which the trunnion pin 28 passes and which permits the pin to play therein when the tractor rises until it reaches a predetermined height.

10 The rising of the tractor when equipped with this attachment causes the front axle assembly to lower until the upper ends of the slots 18 engage the trunnion pin 28 and exert a pull on the cable 20 sufficient to release the clutch. Immediately the clutch is released, the tractor will lower to its normal 20 position.

From the above description it will be obvious that the clutch is automatically released when the tractor rises a predetermined distance, preventing all possibility of 25 the upsetting of the tractor and consequent injury to the driver and the machine.

I claim:—

1. The combination with an engine crank case having laterally spaced depending arms, a casting carried by said arms and composed of two members designed to straddle the front axle, said members being pro-

vided on their opposed inner faces with recesses having centrally disposed laterally extending nipples which fit in apertures in 35 said depending arms and which operate to retain the casting from sliding downward when the tractor rises, the lower ends of said casting members being provided with longitudinally extending slots, a trunnion 40 pin mounted in said slots, a clutch lever, a cable connected with said lever and with said pin whereby a pull is exerted on the cable on the rising of the front axle of the tractor and the clutch lever thereby released. 45

2. An attachment of the class described comprising two separately connected sections to straddle the front axle of a tractor, said sections being provided on their inner faces at their upper ends with laterally extending arms abutting when applied, said arms having bores passing therethrough to receive clamping bolts for securing the members in operative position, and said sections being longitudinally slotted for the passage therethrough of the trunnion pin which connects the axle with the casting. 50

In testimony that I claim the foregoing as my own, I have hereto affixed my signature in the presence of two witnesses.

GEORGE HENRY TRIFTSHAUSER.
